UNITED STATES PATENT OFFICE

JOHN HENRY DODGE, OF SHANNOCK, RHODE ISLAND, ASSIGNOR OF ONE-HALF TO
GEORGE P. CLARK, OF SHANNOCK, RHODE ISLAND

LOOM

Application filed July 13, 1929. Serial No. 378,068.

- This invention relates to an improvement in looms; and has for one of its objects to provide a loom in which the weft supply is not carried in the shuttle but is fed continuously from an extraneous supply source, whereby the loom may be maintained in uninterrupted action for a prolonged period without requiring replacing of the weft thread.
- Another object of the invention is the provision of means for supplying and laying a selvage thread into the margin of the fabric being formed to lock the warp thread at the edge of the fabric.
- The invention further consists in the provision of means for automatically looping the weft thread about the selvage thread to prevent it from being drawn by the returning shuttle back thru the open shed.
- A still further object of the invention is to employ a selvage-forming wire in the margin of the fabric being woven and attach one end of this wire at a point adjacent the selvage thread supply, whereby the act of looping the weft thread over the selvage thread simultaneously loops the same over this selvage-forming wire, which wire assists in forming a smooth selvage on the edge of the fabric and is particularly advantageous when elastic webbing is being woven.
- The invention further consists in the provision of a carrier for the selvage thread having a guiding portion or means whereby the forward lay stroke of the shuttle thread is caused to engage the carrier to be guided by the shape of the carrier around beneath it, and as the thread travels beyond the carrier, the forward end of the carrier is depressed further below the plane of the thread to make sure that this thread on its return lay stroke will pass over the carrier to be looped around the selvage thread.
- With these and other objects in view, the invention consists of certain novel features of construction, as will be more fully described, and particularly pointed out in the appended claims.

In the accompanying drawings:

Fig. 1 is a side elevation showing portions of a loom partly in section and illustrating

my improved device as applied to the loom.

Fig. 2 is a sectional view of one form of shuttle which may be employed in my improved loom and which does not carry a weft thread supply, the weft thread being led from an extraneous source thru the shuttle.

Fig. 3 is a top view showing a portion of a narrow fabric being formed, the lay being in back position and the shuttle on the left side of the fabric and showing my weft thread looping device as mounted on the breast beam of the loom.

Fig. 4 is the same as Fig. 3 but showing the lay in its forward position, the shuttle being now on the right side of the fabric and in position to cause the warp thread to loop about the selvage thread and its supply package.

Fig. 5 is a sectional view of my improved selvage loop-forming device partly in section showing the floating carrier in forward position, which position is taken as the weft thread is being passed around the carrier and is beaten up in the fabric.

Fig. 6 shows the latch as having been actuated by the last forward motion of the lay to move the carrier back into the best position to receive and guide the weft thread around itself and the selvage thread.

Figures 7 and 8 show the members of the carrier supporting arm in section and as spaced apart and also showing the carrier removed from these arm members.

Fig. 9 is a top view showing a portion of the lower arm member with the carrier located in the groove therein.

Fig. 10 is a section on line 10—10 of Fig. 6.

Figures 11 to 14 inclusive are diagrammatic views illustrating different positions of the shuttle; Fig. 11 showing the shuttle in the rear position and on the same side of the fabric as the looping device; Fig. 12 shows the shuttle as having been advanced and as having carried the loop of the weft thread part way around the selvage thread; Fig. 13 shows the shuttle as having been returned to its rear position completing the loop of the weft thread about the selvage thread; and Fig. 14 shows the shuttle as having crossed the fabric thru the shed to the opposite side and as drawing the loop about the selvage thread.

Fig. 15 is a greatly enlarged view showing the arrangement of the warp and weft threads in a fabric and showing the selvage thread as leading from the supply in the carrier with 5 the weft thread looped about the same; also showing the selvage forming wire in the fabric and having one end attached to the carrier and about which wire the weft thread is looped at the same time it is being looped 10 around the selvage thread.

Fig. 16 shows the selvage thread as being led into the margin of the fabric with a weft thread looped thereover, also showing a selvage-forming wire as positioned in the usual 15 way in the margin of the fabric, which wire is not connected to the selvage thread carrier.

It has been found in practice, particularly in the operation of looms for weaving fine silk goods and also looms for weaving very 20 coarse goods that where the weft thread is carried in the shuttle, very frequent replenishing is required; to overcome this important and very objectionable feature of weaving, I have provided an attachment for a loom 25 wherein the weft thread supply is not carried in the shuttle but at a point outside the shuttle and is led thru the shuttle and by it laid into the fabric being woven, and in order to accomplish a weaving operation with this 30 style of shuttle, as the shuttle is passed over and back thru each open shed I lock the loop in the fabric by providing a selvage thread separate from the rest of the warp threads and support the supply package of this selvage 35 thread at a point adjacent the edge of the fabric being formed; means being provided for looping the weft thread over the selvage thread to lock the same into the fabric and prevent this weft thread from being 40 drawn into the fabric by the returning shuttle. In some instances, I also employ a short selvage-forming wire in the margin of the fabric and attach one end of the wire at a point adjacent the selvage thread supply 45 and in such position that as the weft thread is being looped over the selvage thread it is likewise and simultaneously looped over the selvage-forming wire, which wire serves to support the selvage thread against the pull 50 of the shuttle and serves to form a much smoother selvage edge in the fabric; and the following is a detailed description of the present embodiment of my invention and showing one construction of loop-forming 55 device by which these advantageous results may be accomplished in the loom:

With reference to the drawings, 10 designates the usual breast beam of a loom, 11 the 60 cloth take-up roll, and 12 the lay on which the shuttle 13 is caused to travel back and forth to position the warp thread 14 in the fabric 15 being formed.

Instead of employing the usual type of 65 shuttle which carries the weft thread, I mount

a large weft thread supply bobbin 16 on the floor or other convenient place adjacent the loom and lead the thread up thru the tension device 17, the guide eye 18 and thru the longitudinal slot opening 19 in the base of the 70 shuttle 13 and thru the guide eye 20 to the fabric 15 being formed.

This shuttle may be caused, by any of the usual methods, to travel back and forth across the lay, and the lay caused to swing on its 75 pivot 21 forward and back in the usual way. One of the features of my invention is the provision of a simple and effective device for causing the weft thread to be looped automatically around a selvage thread during the 80 weaving operation. One means for accomplishing this looping operation is the arm 22 which is formed in halves secured together by bolts 23, the whole being fixedly mounted upon the breast beam 10 to project rearwardly over the lay when swung to its forward position, as best illustrated in Fig. 4. The members at the free end of this arm are curved away from each other as at 24, forming a space between and these inner curved surfaces are grooved as at 25 to loosely receive 85 between them the opposite side edges of the selvage thread carrier 26 and the extremities of these arms are reduced to form tapered fingers 27 which are spread to form an open 90 mouth 28 to facilitate the entrance of the weft thread thereinto, in order to be passed around this carrier.

This carrier member 26 has a relatively 95 thin oblong body portion which is pointed at its opposite ends. And has a hollow center portion as at 27, in which a selvage package-spool 28 is rotatably mounted on the pin 29. A spring 30 compresses against the spool end and provides the necessary frictional tension 100 on the selvage thread 31. This selvage thread is led from this spool or package up thru the eye 32 in its carrier and across into the margin of the fabric 15 being formed, as best 105 illustrated in Figs. 15 and 16.

In some instances, where my improved 110 loop-forming mechanism is employed, more particularly in the weaving of elastic webbing and the like where a smooth selvage edge is especially desired, it is found of advantage 115 to weave or loop a marginal wire 33 into the selvage as best illustrated in Fig. 15, and to attach one end of this wire to the carrier 26 so that as the weft thread is passed around the carrier 26 to be looped over the selvage thread 31, it is simultaneously looped over this selvage-forming wire 33 which wire then assists 120 in taking the pull of the weft threads as inserted by the shuttle in being carried across the loom.

As this weft thread is beaten up into the fabric, the tension on the selvage thread and also that of the selvage-forming wire 33 serves to draw this loosely floating carrier 26 125 forwardly slightly in its groove between its

supporting arms into the position illustrated in Fig. 5, and in order to force this carrier back and draw outwardly, to a slight degree, the selvage wire and rotate the selvage spool 5 against its friction, I have pivoted at 34 a latch member 35 which is engaged by the forward edge 36 of the projecting member 37 on the lay, causing the upper end of this latch to swing back against the carrier and move it 10 back into the position best illustrated in Fig. 6, where its forward end is depressed to better guide the thread thereover on its return stroke its rear end being slightly raised to better permit the passing of the next forwardly moving weft thread around beneath it. 15

The operation of my invention may be more particularly described as follows:—

The weft thread 14 is led from the package 16 thru the tension 17, guide eye 18 and thru the slot in the back of the shuttle and thru the guide eye 20 in the front of the shuttle to the fabric being formed.

My improved weft thread looping device 25 may be mounted on either one or both side edges of the fabric 15 being formed but for convenience I have herein shown the device as being mounted on one edge only of the fabric.

As the shuttle is now driven across the lay 30 to the side of the looping device 22 it goes a short distance beyond this device in which is loosely supported the floating carrier 26 with its axis at a right angle to the weft thread 35 from which carrier is led the selvage thread 31 into the margin of the fabric. As the lay now comes forward into the position best illustrated in Figs. 4 and 12, the eye 20 of the shuttle is carried forwardly beyond the forward end of the carrier a distance sufficient 40 to draw the weft thread into the mouth 38 of this looping device to be guided by the edge of the carrier around the under edge of the carrier and owing to the fact that the 45 position of this shuttle eye 20 is in a plane above that of the forward end 29 of the carrier, this loop is caused to automatically pass around and above this forward pointed extremity of this carrier and back over its upper edge as the lay swings back, looping the 50 weft thread about the selvage thread. Immediately after the weft thread has passed around this forward pointed end of the carrier the push member 37 on the lay engages the latch 35 causing it to engage and force back the carrier into the position illustrated in Fig. 6, ready to receive the next weft thread. When the lay is swung back to its rearward position, the shuttle is then returned thru the open shed into the position illustrated in Fig. 14 and the harnesses 40 are now moved to change the shed, after which the mechanism repeats the operation above described.

By the use of my improved loop-forming

device, the weft thread is automatically looped about the selvage thread which serves to lock this loop at the margin of the fabric and prevent it from being drawn thru the shed and by supplying the weft thread from a source outside of the shuttle the loom may be run almost indefinitely without attention to the weft supply. 70

The foregoing description is directed solely towards the construction illustrated, but I desire it to be understood that I reserve the privilege of resorting to all the mechanical changes to which the device is susceptible, the invention being defined and limited only by the terms of the appended claims. 75

I claim:

1. In a loom, a lay, a shuttle on the lay, means for leading the weft thread thru the shuttle from an extraneous source of supply, means for supporting a selvage thread supply adjacent the edge of the fabric and leading the selvage thread therefrom to the fabric being formed, and means in said selvage thread support affected by action of the lay for guiding the weft thread around said selvage thread. 80

2. In a loom, a lay, a shuttle on the lay, means for leading the weft thread thru the shuttle from an extraneous source of supply, means for supporting a selvage thread supply adjacent the edge of the fabric and a selvage thread leading from such supply into the fabric being formed, and means in said selvage thread support affected by the last end of the forward and first portion of the backward motions of the lay for guiding the weft thread around said selvage thread. 95

3. In a loom, a lay, a shuttle on the lay, means for leading the weft thread of the shuttle from an extraneous source, a floating carrier positioned with its axis at right angles to the weft thread and tapering towards its opposite ends for supporting a selvage thread supply and located adjacent the edge of the fabric being formed, and means whereby the swing of the lay positions said carrier and causes the weft thread to be looped about said carrier and its selvage thread. 105

4. In a loom, a lay, a shuttle on the lay, an arm mounted in the loom adjacent one edge of the fabric being formed to extend rearwardly over the lay when swung to forward position, said arm being forked at its free end presenting spaced fingers for guiding the thread thereinto between them, a floating selvage thread carrier loosely supported between said fingers from which a thread is led into the margin of the fabric, and said carrier having a thread-guiding surface for looping that portion of the weft thread between the fabric and the shuttle about the said selvage thread by action of the lay. 120

5. In a loom, a lay, a shuttle on the lay, an arm mounted in the loom adjacent one edge of 130

the fabric being formed to extend rearwardly over the lay when swung to forward position, said arm being forked at its free end presenting spaced fingers for guiding the thread into the space between said fingers, a floating carrier for the selvage thread located between said fingers, a bobbin in said carrier from which a thread is led to the margin of the fabric, and said carrier having a thread-guiding surface whereby the swing of the lay moves the shuttle forward and back to pass the weft thread between said fingers to be engaged by said guiding surface and conducted under and over the carrier to loop it about the selvage thread.

6. In a loom, a lay, a shuttle on the lay, means for leading the weft thread thru the shuttle from an extraneous source, a carrier for supporting a selvage thread supply adjacent the edge of the fabric and leading a selvage thread therefrom to the fabric being formed, a selvage-forming wire also leading from a carrier into the margin of the fabric, and means for passing the weft thread over both the selvage thread and the selvage-forming wire.

7. In a loom, a lay, a shuttle on the lay, means for leading the weft thread thru the shuttle from an extraneous source, a carrier for supporting a selvage thread supply adjacent the edge of the fabric and leading a selvage thread therefrom to the fabric being formed, a selvage-forming wire also leading from a carrier into the margin of the fabric, and means controlled by the movement of the lay for passing the weft thread over both the selvage thread and the selvage-forming wire.

8. In a loom, a lay, a shuttle on the lay, means for leading the weft thread thru the shuttle from an extraneous source, a carrier for supporting a selvage thread supply adjacent the edge of the fabric and leading a selvage thread therefrom to the fabric being formed, a selvage-forming wire also leading from a carrier into the margin of the fabric, means for passing the weft thread over both the selvage thread and the selvage-forming wire, and means for adjusting the position of the carrier upon each forward motion of the lay.

9. In a loom, a lay, a shuttle on the lay, means for leading the weft thread thru the shuttle from an extraneous source, a carrier for supporting a selvage thread supply adjacent the edge of the fabric and leading a selvage thread therefrom into the fabric being formed, a selvage-forming wire also leading from a carrier into the margin of the fabric, means for passing the weft thread over both the selvage thread and the selvage forming wire, and a latch actuated by movement of the lay to readjust the carrier upon each forward movement of the lay.

10. In a loom, a lay, a shuttle on the lay, an arm mounted in the loom adjacent one edge

of the fabric being formed to extend rearwardly over the lay when swung to forward position, said arm being forked at its free end presenting spaced fingers for guiding the thread thereinto between them, said fingers being grooved on their inner surfaces, a floating selvage thread carrier loosely supported in said grooves between said fingers from which a thread is led into the margin of the fabric, a selvage-forming wire also led from said carrier into the fabric, and means for passing that portion of the weft thread between the fabric and the shuttle over the said selvage thread and wire.

11. In a loom, a lay, a shuttle on the lay, a carrier support adjacent the edge of the fabric being formed, a carrier loosely mounted in said support, a bobbin rotatably mounted in said carrier from which a selvage thread is led into the fabric being formed, a selvage forming wire having one end attached to said carrier and having a portion leading into the margin of the fabric, and means affected by the action of the lay for looping the weft thread around both the selvage thread and the wire simultaneously.

12. In a loom, a lay, a shuttle, means for leading the weft thread through the shuttle from an extraneous source of supply, a carrier provided with means for connecting a selvage thread and a selvage wire thereto, and means responsive to action of the lay for conducting the weft thread about the carrier to be looped about its selvage thread and the selvage wire leading therefrom.

13. In a loom, a lay, a shuttle, means for leading the weft thread through the shuttle from an extraneous source of supply, a floating carrier for supporting a selvage-thread supply, means in the carrier for attaching a selvage wire thereto and means in the carrier responsive to action of the lay for conducting the weft thread about the carrier to be looped about both its selvage thread and the selvage wire leading therefrom.

14. In a loom, a lay, a shuttle, means for leading the weft thread through the shuttle from an extraneous source of supply, carrier for supporting a selvage-thread supply, and a guiding surface on said carrier responsive to action of the lay for conducting the weft thread about the carrier and its selvage thread.

15. In a loom, a lay, a shuttle, means for leading the weft thread through the shuttle from an extraneous source of supply, a carrier for supporting a selvage-thread supply, and said carrier being provided with an inclined surface for conducting the weft thread from the shuttle as advanced by the lay about the selvage thread.

16. In a loom, a lay, a shuttle, means for leading the weft thread through the shuttle from an extraneous source of supply, a carrier for supporting a selvage-thread supply,

and said carrier being provided with a thread guiding edge to conduct the weft thread first beneath it and over its upper edge by action of the lay.

5 17. In a loom, a lay, a shuttle, means for leading the weft thread through the shuttle from an extraneous source of supply, a carrier for supporting a selvage thread supply, said carrier being shaped to engage the weft
10 thread carried by the shuttle on the lay to conduct this thread about it and its selvage thread by action of the lay.

18. In a loom, a lay, a shuttle, means for leading the weft thread through the shuttle from an extraneous source of supply, a carrier for supporting a selvage-thread supply, the axis of said carrier being disposed substantially at right angles to the weft thread and said carrier being tapered at its ends to
20 engage and conduct the weft thread about the selvage thread by action of the lay.

19. In a loom, a lay, a shuttle, means for leading the weft thread through the shuttle from an extraneous source of supply, a floating carrier supporting a selvage-thread supply, means in said carrier for conducting the weft thread beneath it as advanced by the lay, and means operated by the lay for subsequently moving the carrier into a position,
25 30 whereby a return of the lay will assist in causing the weft thread to ride over the carrier and so loop the weft thread about the selvage thread.

In testimony whereof I affix my signature.
35 JOHN HENRY DODGE.
